UNITED STATES PATENT OFFICE.

GOTTLOB FUEGEL AND HERMAN SCHMID, OF BROOKLYN, NEW YORK, ASSIGNEES, BY
MESNE ASSIGNMENTS, TO APOLLO MAGNETO CORPORATION, OF BROOKLYN, NEW
YORK, A CORPORATION OF DELAWARE.

GEAR CONSTRUCTION.

1,415,542.

Specification of Letters Patent. Patented May 9, 1922.

Application filed December 27, 1918. Serial No. 268,555.

To all whom it may concern:

Be it known that we, GOTTLB FUEGEL and HERMAN SCHMID, who were formerly subjects of the German Emperor, but who have 5 severally renounced all allegiance to said potentate and declared our intentions of becoming citizens of the United States, residing in Brooklyn, in the county of Kings and State of New York, have invented certain 10 new and useful Improvements in Gear Constructions, of which the following is a specification.

Our invention relates to improvements in gear construction; particularly gear construction 15 for the distributor mechanism of magnetos used in the ignition systems of internal combustion engines.

An object of our invention is to provide 20 a gear wheel secured to the element by which it is rotatably supported so as to form there- with a strong, durable and efficient unit; and to produce such a unit by a method that 25 is quite inexpensive and involves a small number of operations; whereby our proved gear construction can be manufactured in large quantities quickly and at low cost.

A further object of our invention is to 30 provide a gear construction that is quite simple and made up of relatively few parts capable of being readily and easily assembled.

These and other objects and advantages of 35 our invention are fully set forth in the following description, taken in connection with the accompanying drawings; forming a part of the same; and the novel features of our improvement will be precisely defined in the appended claims. This disclosure however, is explanatory only, and we 40 reserve the right to resort to changes in the shape, size and arrangement of parts, within the scope and spirit of our invention, to the full extent indicated by the general 45 meanings of the terms in which the claim is expressed, and by variations in the wording of same.

On the drawings.

Figure 1 is a sectional view of an element, such as a shaft or journal, on which the gear wheel in our improved gear construction is mounted.

Figure 2 is a longitudinal section through

a gear construction according to our invention as it appears when completed; and 55

Figure 3 is a front elevation of the parts shown in Figure 2, presenting a fragment of the wheel, the remainder being illustrated in broken lines only.

The same numerals of reference identify 60 the same parts throughout.

In the particular description of the embodiment of our invention herein illustrated, we indicate at 1 a gear wheel that can be made of fibre or any other suitable 65 substance, and of any desired size or number of teeth, as will be understood. This gear wheel will be mounted upon a shaft or journal 2, and the gear wheel and its journal will be permanently united together to 70 form a single unit. Preferably the journal 2 is made of metal and is both cylindrical and tubular so as to enable us to save material and make the journal light in weight. As shown particularly in Figure 1, the ele- 75 ment 2 is reduced at one end to provide a shoulder 3; and, before it is united to the gear 1, the bore of the shaft 2 will be of uniform diameter throughout.

The gear wheel 1 has a central opening 4 80 of the same diameter as the reduced outside diameter of the shaft 2, adjacent the shoulder 3, and on one face the gear wheel will be counterbored to provide a shoulder 5 concentric with the opening 4.

To assemble the wheel 1 and shaft 2, we first take a washer 6 and slip it over the reduced end of the shaft until it abuts against the shoulder 3. The gear is then placed upon the shaft 2 by inserting the reduced 90 end of the shaft into the central opening 4 and causing the washer or collar 6 to make contact with the face of the wheel 1 opposite to the face having shoulder 5. In this position the reduced end of the shaft 2 will project beyond the shoulder or recess 5. Next we apply a washer or collar 7, placing the same upon the reduced end of the shaft and slipping it into the recess 5, which forms a seat for this washer. The washer 7 will be 95 110 of such dimensions as to fit the shaft and recess snugly so as to provide for making these parts perfectly tight when the construction is finished.

In order to make a permanent union be- 105 tween the gear and shaft, the end of the

shaft adjacent the collar 7 is expanded as indicated in Figure 2. The expansion can be produced in almost any manner by suitable machines or tools and it results in crowding the metal at the reduced end of the shaft against the collar 7; whereby the gear is forced tightly against the collar 6 and the gear and shaft bound together. The operation is completed by drilling a hole between the shaft 2 and the collar 7 and driving in the same a pin or rivet 8, which further assures a tight connection between the gear wheel and shaft and obviates any likelihood of the wheel turning on the shaft 2 when one uses the gear under practical conditions.

The washer 7 may be chamfered along one of its inner edges, as indicated at 9 in Figure 2, to make room for the expanded end 20 of the shaft 2; and the end of the shaft may be ground off so as to be flush with this washer to give a neat, finished appearance. Between the two washers 6 and 7 the wheel is caused to be gripped securely, owing to 25 the manner in which these washers are held by the shaft between the expanded end thereof and the shoulder 3.

By the above method we obtain a gear construction that is well adapted for the 30 purpose in view, can be produced in large quantities at small cost and in standard sizes; so that they can be used for the de-

sired purpose and easily replaced when worn or broken.

The gear wheel 1 may be also have openings 10 therein for fastening devices to enable the insulated rotatable brush of the distributor mechanism to be secured to it; and the wheel further may be marked with an "R" and an "L" to indicate the points at 40 which it must engage with a given point on the driving gear, carried by the armature of the magneto, for right and left hand rotation.

Having described our invention which we 45 believe to be new and desire to secure Letters Patent of the United States is:

The combination of a gear wheel having a central opening and a shoulder surrounding said opening, a washer engaging said shoulder, a hollow shaft having a shoulder at one end and a washer engaging the shoulder on said shaft, the gear wheel being fitted upon the shaft so that the gear wheel engages the washer on the shaft, the end of the 55 shaft being expanded against the washer on the gear wheel, and a pin to engage the shaft and said last named washer.

In testimony whereof, we have signed our names to this specification this 1st day of 60 November, 1918.

GOTTLÖB FUEGEL.
HERMAN SCHMID.
